UNITED STATES PATENT OFFICE.

JOSEPH WRIGHT, OF PHILADELPHIA, PENNSYLVANIA.

DESIGN FOR AN UMBRELLA OR PARASOL.

SPECIFICATION forming part of Design No. 12,602, dated December 13, 1881.
Application filed October 13, 1881. Term of patent 7 years.

To all whom it may concern:

Be it known that I, JOSEPH WRIGHT, a citizen of the United States, residing in Philadelphia, Pennsylvania, have invented or produced 5 a new and original Design for an Umbrella or Parasol, of which the following is a specification.

- My design for an umbrella or parasol is fully shown in the accompanying drawing.
- 10 The design comprises the handle and the tip, the handle being made in imitation of a lawn-tennis racket and the tip being furnished with a representation of a tennis-ball.

I claim—

The design comprising the handle made in imitation of a tennis-racket and the tip furnished with a representation of a tennis-ball, as shown and described.

In testimony whereof I have signed my name to this specification in the presence of two subscribing witnesses.

JOSEPH WRIGHT.
